UNITED STATES PATENT OFFICE.

WILLIAM W. SCOTT, CHRISTIAN E. HEISE, AND CYRUS H. BLOSSOM, OF ALGONA, IOWA.

KNOCKDOWN BOX.

SPECIFICATION forming part of Letters Patent No. 356,854, dated February 1, 1887.

Application filed July 31, 1886. Serial No. 209,604. (No model.)

To all whom it may concern:

Be it known that we, WILLIAM W. SCOTT, CHRISTIAN E. HEISE, and CYRUS H. BLOSSOM, citizens of the United States of America, and 5 residents of Algona, in the county of Kossuth and State of Iowa, have invented a Knock-down Box, of which the following is a specification.

Our object is to save expense in storing and 10 shipping merchandise in boxes by providing strong and durable boxes that can be readily folded together compactly when empty, as required to facilitate handling and economizing space, and also readily adjusted and filled 15 and closed without nailing and damaging the cover and the top edges of the box, as required to preserve them to be repeatedly filled and shipped and returned empty and folded.

Our invention consists in the construction 20 and combination of the four sides of a box, a loose bottom, a hinged cover, and a loose partition, as hereinafter set forth, pointed out in our claims, and illustrated in the accompanying drawings, in which—

25 Figure 1 is a top view showing our box open and ready to be filled with merchandise. Fig. 2 shows it folded as required for storing and shipping when empty. Fig. 3 is a perspective view showing it filled, closed, and 30 ready to ship.

35 A are the wooden sides, and B the ends, of a box, that may vary in size as desired. Each side overlaps the square end of one of the end pieces, B, and is secured thereto by means of 40 hinges c, that are fastened against the inside faces of the pieces A and B. The opposite ends of the same pieces A and B are mitered and secured to the correspondingly-mitered ends of the other two pieces A B by hinges d, that are fixed against their outside faces, as clearly shown in Figs. 1, 2, and 3.

1 2 3 4 are metal strips fixed against the inside faces of the parallel sides A and bent inward at right angles at their lower ends to 45 support the bottom of the box.

5 6 7 8 are notches in the lower edges of the sides A and ends B, that admit the horizontal portions of the bottom supports, 1 2 3 4, when the box is folded, as clearly shown in Fig. 2.

f are cleats fixed against the outside faces 50 of the pieces B, to re-enforce them, to serve as handles, and also to project upward to overlap the ends of the hinged cover when the box is closed, as clearly shown in Fig. 3.

G is a cover mitered and hinged to the top 55 edge of one of the sides A that projects above the ends B.

H is a loose bottom resting upon the series of fixed supports 1 2 3 4, as shown in Fig. 1.

J is a loose partition resting upon the bottom H and retained in a vertical position by means of cleats k, fixed against the inside faces of the sides A in such a manner that when the cover is closed it will rest upon the top edge of the partition and prevent the bottom from 65 becoming displaced.

m is a hook pivoted to the front face of the box to engage an eye, n, fixed to the front edge of the cover, as required to retain the cover closed. A hasp or other suitable lock may be 70 substituted for the hook and eye.

We claim as our invention—

1. The wall of a box that is mitered together at two corners and secured together by means of hinges fixed on the outside, and square-jointed and secured together at the other two corners by means of hinges fixed against the inside, to operate in the manner set forth, for the purposes stated. 75

2. The bottom supports, 1 2 3 4, in combination with the hinged wall-sections A, having notches 5 6 7 8, for the purposes stated. 80

3. The knockdown box comprising the two parts A and the two parts B, mitered and hinged together at two corners and overlapped 85 and hinged together at the other two corners, fixed stops to support a removable bottom, a loose bottom, a hinged cover, and a removable partition, substantially as shown and described, for the purposes stated.

WILLIAM W. SCOTT.
CHRISTIAN E. HEISE.
CYRUS H. BLOSSOM.
